WALL PAPER.

No. 20,224.

Patented Oct. 21, 1890.

UNITED STATES PATENT OFFICE.

CHARLES BOOZE, OF BUFFALO, NEW YORK, ASSIGNOR TO M. H. BIRGE
& SONS, OF SAME PLACE.

DESIGN FOR WALL-PAPER.

SPECIFICATION forming part of Design No. 20,224, dated October 21, 1890.

Application filed September 27, 1890. Serial No. 366,377. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying photograph, forming part thereof.

10 The leading feature of my design consists of a spray of leaves and flowers arranged horizontally and inclosed in an ornamental border formed of connected braces or ogee lines forming the top and bottom of the border and upright stencil ornaments with a rosette in the center, forming the ends of the border, as represented in the accompanying

photograph. A wide band with a narrow band on each side is arranged horizontally above the border, and a series of parallel lines 20 are arranged horizontally and below the border. The border is printed in color upon a light-tinted background.

My design is more particularly designed for and used as a ceiling decoration. 25

What I claim is—

The design for wall-paper herein shown and described.

Witness my hand this 13th day of September, 1890.

CHARLES BOOZE.
